UNITED STATES PATENT OFFICE.

JAMES O'CONNOR, OF NEW YORK, N. Y., ASSIGNOR TO AUTOPIANO CO., OF NEW YORK,
N. Y., A CORPORATION OF NEW YORK.

TRACKER AND GUIDE APPARATUS FOR TRAVELING WEBS.

1,160,193.

Specification of Letters Patent. Patented Nov. 16, 1915.

Application filed January 4, 1905, Serial No. 239,682. Renewed December 26, 1914. Serial No. 879,233.

To all whom it may concern:

Be it known that I, JAMES O'CONNOR, a citizen of the United States, and resident of New York, in the county of New York and State of New York, have invented certain new and useful Improvements in Tracker and Guide Apparatus for Traveling Webs, of which the following is a full, clear, and exact specification.

10 This invention relates to improved means for guiding a traveling sheet or web so as to keep it in proper operative relation to the mechanical devices with which it is employed, the object being to automatically 15 maintain the sheet in proper relation to its associated devices by means of the margins of the sheet or web itself, without any perforation or cutting or other special preparation of the sheet and without in any way 20 injuring the edges of the most delicate or fragile fabric.

Figure 1 of the drawings is a plan view of my preferred embodiment of this invention showing it as applied to the guiding 25 of a perforated sheet for controlling the operation of self-playing musical instruments and similar machines. Fig. 2 is an end view of the apparatus in section through the line 2—2 of Fig. 1. Fig. 3 is a plan 30 view of a portion of the apparatus showing some of the parts in a different position from that represented in Fig. 1. Figs. 4 to 7 inclusive are sectional side views of one set of the pneumatic operating devices showing 35 them in four different positions. Figs. 8 to 11 are similar views of another set of the pneumatic operating devices. Fig. 12 is a fragmentary plan view in enlarged scale, of a part of the mechanism shown in Fig. 1. 40 Fig. 13 is a side view of the parts of Fig. 12 in section in the line 13—13 of Fig. 12. Figs. 14, 15 and 16 are side views of three modifications of the pneumatic operating devices, all three of the modifications being shown 45 with their parts in the position occupied by them when the sheet or web is traveling in its normal path. Fig. 17 is a fragmentary view showing a modified arrangement of the tracker apertures. Fig. 18 is a fragmentary view of a modified valve device.

The employment of a traveling sheet or web in connection with mechanical devices

is attended with well-recognized difficulties, prominent among which is the trouble arising from the sidewise shifting of the sheet 55 or web from its normal path of travel whereby it is thrown out of proper lateral register with its associated devices. While this arrangement is more or less troublesome wherever a traveling sheet or web is employed, it is particularly so in the case of 60 that class of mechanical musical instruments which use a perforated sheet in connection with a tracker to control the action of note sounding devices, as in this class of instruments it takes but a very slight divergence 65 of the sheet from its normal path to seriously impair the rendition of the music.

In my U. S. Patent No. 789053 of May 2, 1905 is shown, described and claimed that 70 portion of the present apparatus which operates to bring the sheet and the tracker again into proper coincidence whenever any sidewise divergence of the sheet takes place.

The means which accomplish this result consist of a pair of pneumatic motors secured to opposite ends of the tracker bar. Each 75 motor is provided with an arm extending from its movable leaf near the hinge end, which arm engages a collar on the winding 80 shaft of the note sheet. The operation of these motors is inaugurated by means of two oppositely disposed special apertures placed near the tracker ends, which apertures are covered by the unperforated margins of the 85 sheet when the sheet is traveling in its normal path, but which are uncovered at one side or the other when the sheet diverges laterally, thus causing the collapsing of one or the other of the motors according to which 90 of the two apertures is uncovered. The collapsing of the motor causes the arm on the movable leaf to push the winding shaft in one direction, thus carrying the winding roll in that direction, and with it the note 95 sheet, thereby bringing the latter back into proper register with the tracker apertures. If preferred, the tracker may be mounted to shift endwise, and in that case a suitable abutment is arranged for engagement with 100 the motor arm, so that the collapsing of the motor shifts the tracker in the proper direction.

The apparatus of the present invention is

herein shown in connection with the apparatus of the said patent, and performs the additional function of adjusting the aforesaid special apertures to varying widths of the sheet, caused by lateral contraction or expansion of the material, or otherwise. It operates to move each aperture outward toward its adjacent edge when the sheet expands, and to push each aperture inward toward the center of the sheet when the sheet contracts, this keeping the two special apertures always just inside the traveling edges of the sheet, so that the sidewise divergence of the sheet will uncover one or the other of the apertures.

The note sheet 18 is carried on the rolls 21 and 22 situated on opposite sides of the tracker 19, and is assumed to be traveling in the direction of the arrow 24, motion being imparted through the pulley 23 to the roll 22 by any suitable mechanism. The tracker 19 rests at its right hand end in a channel provided for it in the block 55, which in turn is supported in the frame 27. The left hand end of the tracker 19 is similarly supported in the block 56 which in turn is supported in the frame 28. The supporting blocks 55 and 56 are provided with shelves 103 and 94, upon which rest in suitable ways the sliding blocks 41 and 42, which carry the apertures 39 and 40 respectively. The strips 111 and 93 may be used if required, to keep the sliding blocks in their ways. The apertures 39 and 40 are located so that they are covered by the unperforated margins of the sheet 18 when it is traveling in its normal path, as shown in Fig. 1. As thus far described the apparatus is substantially as shown in the patent referred to, excepting that in the patent the special apertures 29 and 30 are adapted to be manually adjusted to suit different widths of paper, whereas in the present inventions the corresponding apertures 39 and 40 are adapted to be adjusted automatically by means, which will next be described. In that case the set screws 44 serve to hold the bearings 26 in a fixed position in the frame uprights. The aperture 39 is connected by means of the tube 37 with customary primary pneumatic devices in the exhaust chest 20, to which is also connected the tube 35, leading to the interior of the motor bellows 33. This bellows is secured to the tracker 19 and is provided with an arm 31, the outer end of which is in contact with the lug 29 on the bearing 26, seated in a slot in the upright 27 and forming the journal of the right hand end of the shaft 25, to which the roll 21 is secured. The aperture 40 is similarly connected by means of the tube 38, the exhaust chest 16 and the tube 36 to the motor bellows 34, also secured to the tracker, and similarly provided with an arm 32 which is

in contact with the lug 30 on the left hand bearing 26 secured to the upright 28.

The supporting block 55 is provided with an inner aperture 51 and an outer aperture 53, the former of which is just inside, and the latter just outside the right hand edge 49 of the sheet 18 when the sheet is traveling in its normal path. The supporting block 56 is provided with similar apertures 52 and 54 similarly placed with reference to the left hand edge 50 of the sheet 18. The inner aperture 51 is connected by means of a tube 59 with the passage 69, leading to the interior of the primary bellows 67 contained within the exhaust chamber 71 of the primary box 65. A tube 66 connects the chamber 71 to a suitable exhausting apparatus. The movable leaf of the bellows 67 supports the stem 78 of the valve 77 contained in the chamber 72, and resting upon and covering the opening 83, which leads from the chamber 71 to the chamber 72. A channel 80 which enters the chamber 72 over the valve 77 connects the chamber with the outside air. A passage 79 connects the chamber 72 with the chamber 73, in which is situated a primary bellows 68 connected by the passage 70 and the tube 60 with the inner aperture 52. The valve 84 rests upon and closes the opening 86 between the chamber 73 and the chamber 74, the valve being provided with a stem 85, the end of which is in contact with the movable leaf of the bellows 68. An opening 89 over the valve 84 connects the chamber 74 with the outside air. From another part of the chamber 74 a tube 90 extends to the motor bellows 91 secured to the left hand end of the tracker 19.

The outer aperture 53 is connected by means of a tube 61 to the passage 128 leading to the interior of the primary bellows 126 contained in the exhaust chamber 125 of the primary box 121. A tube 143 connects the chamber 125 with exhausting apparatus. The valve 133 is held by the bellows 126 when the latter is inflated, against the opening 138, the stem 132 of the valve carrying on its upper end the pallet 134. A passage 137 which opens into the chamber 122 under the pallet 134 connects the chamber with the outside air. The chamber 125 contains also the primary bellows 127 connected by means of the passage 131, and the tube 62 with the outer aperture 54. The bellows 127 supports the valve stem 139 and when inflated keeps the valve 140 against the opening 141 which is connected by means of the tube 120 with the motor bellows 116 secured to the right hand end of the tracker 19.

By the above described arrangement a dual or coöperating control is provided for each of the motor bellows 91 and 116, so that it is only by affecting both apertures of either pair that any effect can be produced on the corresponding motor bellows. A, examina-

tion of Figs. 4 to 7 inclusive will make this clear as to apertures 51 and 52 and the motor bellows 91, while an examination of Figs. 8 to 11 inclusive will similarly indicate the relation of the apertures 53 and 54 and the motor bellows 116. This dual control will be more particularly explained in describing the consecutive operation of the parts.

10 The motor bellows 116 is provided with an arm 115, the outer end of which is connected by means of the rod 114 to the lug 113 on the sliding block 41. The other side of the block is provided with a lug 102 which is connected by means of the rod 101 with the link 97. The latter is pivoted at its center on the bracket 98 secured to the tracker, and is also connected at its outer end by means of the rod 95 to the outer end 15 of the arm 92 appurtenant to the motor bellows 91. The inner end of the link 97 is connected by the rod 99 to the lug 100, appurtenant to the sliding block 42. The sliding block 41 is normally held in a central 20 position upon its supporting shelf 103 by means of springs 104 and 107 (Figs. 12 and 13) which are secured to the shelf 103 and have their free ends in engagement with the opposite sides of the block 41, each spring 25 when at rest having one side in contact for the greater part of its length with the adjacent side of the shelf 103, thus releasing its pressure on the sliding block 41 as soon as the corresponding edges of the block and 30 the shelf coincide. Adjustable stop screws 108 and 109 appurtenant to the shelf 103 regulate and limit the movement of the block 41 in either direction by engaging the lug 110 appurtenant to the block.

35 In the normal position of the sheet as shown in Fig. 1, the two apertures 51 and 52 are both covered by the unperforated margins of the note sheet 18, while the two apertures 53 and 54 are both open to the 40 atmosphere. The closed condition of the two apertures 51 and 52 keeps the primary bellows 67 and 68 both collapsed, so that there is no communication between the motor bellows 91 and the exhaust chamber 71.

45 While the sheet is in its normal position the motor bellows 91 is thus allowed to remain partly open and is free to open still wider if desired. On the other hand the two apertures 53 and 54 being open to the atmosphere 50 keep the primary bellows 126 and 127 both inflated, so that the motor bellows 116 is cut off from communication with the exhaust chamber 125, thus leaving the motor bellows 116 at rest in a partly open condition, and 55 free to open still wider if required.

Secured to one side of the tracker 19 and preferably near its center, is the bracket 152 in which is journaled the central portion 60 preferably of the adjusting screw 151. Collars or other means are provided to prevent

longitudinal movement of the screw in the bracket. The screw 151 has at either end threaded portions 154 and 155, the threads being right hand in one portion and left hand in the other. These threaded portions 70 fit within the lugs 156 and 157, which are tapped out to receive them and are appurtenant to the support blocks 55 and 56. A knob or head 153 is provided by which the screw may be rotated by hand to move the 75 blocks 55 and 56 toward or from each other. This movement permits the adjustment of the position of the apertures 51, 52, 53 and 54, to conform to the normal width of different note sheets, this width varying somewhat even among sheets of the same nominal width. The character of the paper, the atmospheric conditions in which it is perforated and the varying standards used by different manufacturers are some of the 80 causes of these differences in width.

The operation of the parts is as follows:— The sheet 18 having been placed in position upon the rolls 21 and 22 and extending over the tracker 19, the adjusting screw 151 is 90 turned to bring the two outer apertures 53 and 54 outside the edges 49 and 50 respectively of the sheet, and the two inner apertures 51 and 52 inside their respective edges of the sheet. In making this adjustment the 95 supporting blocks 55 and 56 slide toward or from each other in their seats in the uprights 27 and 28, the tracker 19 remaining stationary during this movement as the lug 152, in which the screw 151 is journaled against 100 endwise movement, is fixed to the tracker and thus always keeps the blocks 55 and 56 equidistant from the lateral center of the tracker. The supporting block 55 carries the sliding block 41 with it as the springs 105 104 and 107 keep the block 41 centrally upon the shelf 103 appurtenant to the block 55. The sliding block 42 also moves uniformly with the supporting block 56 on account of the motion imparted to it by means of the 110 connecting rod 99, the link 97, and the connecting rod 101. The motor bellows 91 and 116 are opened or closed a little, as the case may be, by this adjusting movement on account of their connection with the sliding blocks 41 and 42 through the connecting rods 114 and 95. The mechanism being set in motion, if the sheet diverges from its normal path to the left, for instance, the apertures 115 51 and 39 will both be uncovered while the 120 aperture 54 will be closed. The uncovering of the aperture 51 alone has no effect, but the effect of uncovering the aperture 39 also is to put the motor bellows 33 in communication with the exhaust chest 20, thus collapsing the bellows and causing it to move to the left as the arm 31 is in contact with the stationary lug 29. The bellows 33 being fixed to the tracker 19 carries the latter with it, thus restoring the note-sounding aper- 125 130

4

tures to proper register with the perforations of the note sheet 18, the supporting blocks 55 and 56 in which the tracker is seated, as well as the sliding blocks 41 and 42, also moving with the tracker on account of the connection through the screw 151. This motion therefore carries the apertures 39 and 51 again under the margin of the sheet, thus releasing the air pressure on the 10 bellows 33, while the aperture 54 is restored to its normal position outside of the edge 50 of the sheet. Before this restoration takes place, however, the uncovering of the aperture 51 causes the primary bellows 67 to expand (Fig. 6), thus raising the valve 77, closing the outside air passage 80, and permitting the chambers 72 and 73 to exhaust through the passages 83 and 79. No further effect is produced, however, as the primary 20 bellows 68 still remains collapsed on account of the covered condition of the aperture 52, and the restoring of the aperture 51 to its normal position inside the edge of the sheet permits the primary bellows 67 to again collapse (Fig. 4). Similarly, the closing of the aperture 54 operates only to collapse the primary bellows 127 (Fig. 11) and the restoring of the aperture to its normal position permits the primary bellows 127 to expand once more (Fig. 8). On the other hand, if the sheet diverges to the right, so as to uncover the apertures 40 and 52 and cover the aperture 53, the tracker 19 will be brought into proper register by the action of 30 the motor bellows 34. The uncovering of the aperture 52 produces no effect on the primary bellows 68 as the chamber 73 fails to exhaust, being still in communication with the outside air through the passages 79 and 80. (Fig. 7.) Similarly the closing of the aperture 53 operates only to collapse the primary bellows 126 (Fig. 10) both bellows being restored to their normal conditions (Figs. 4 and 8) as soon as the tracker shifts. 40

If the sheet 18 expands instead of shifting, the apertures 53 and 54 will both be covered (Fig. 9), thus causing the two primary bellows 126 and 127 to collapse. The collapsing of the former permits the pallet 134 to be pressed downward by the spring 135 against the outside opening 137, thereby exhausting the chamber 122 as the action of the spring 135 also causes the valve 133 to drop, and open the passage 138 between the chambers 122 and 125. The collapsing of the primary bellows 127 allows the valve 140 to drop, thus uncovering the passage 141 and causing the motor bellows 116 to collapse through its communication with the 50 chamber 122 by the tube 120. The collapsing of the bellows 116 draws the sliding block 41 to the right along the shelf 103, the spring 104 yielding to permit the block to move (Fig. 3). The block 42 is moved correspondingly to the left through the action 60 of the connecting rod 101, the link 97 and the connecting rod 99, the motor bellows 91 being made to expand still farther by this action since the arm 92 is connected by the rod 95 to the link 97. The outward movement of the two sliding blocks 41 and 42 thus brings their corresponding apertures 39 and 40 close to the edges 49 and 50 of the sheet again, and places them in readiness to perform their functions in case the sheet 70 shifts in either direction. The parts will remain in this position as long as both apertures 53 and 54 remain covered by the margins of the sheet. As soon as either one or both are again uncovered by the narrowing 80 of the sheet or a sidewise change in its position, communication between the motor bellows 116 and the exhaust chamber 125 will be broken, thus allowing the springs 104 to slide the blocks 41 and 42 to their normal 85 position. If now the sheet 18 contracts appreciably from normal width it will uncover the two apertures 51 and 52 (Fig. 5) and the two apertures 39 and 40. The primary bellows 67 will expand and cause the valve 77 to rise and close the opening 80 to the atmosphere, thus exhausting the chambers 72 and 73. The exhaustion of the latter chamber causes the primary bellows 68 to expand, since its interior is open to the atmosphere through the tube 60. The valve 84 will now rise so that it closes the opening 89 to the atmosphere, thereby allowing the chamber 74 to exhaust and causing the motor bellows 91, which is in communication with 90 the chamber 74 through the tube 90, to collapse and draw the connecting rod 95 to the left. This swings the link 97 on its pivot, and causes the two blocks 41 and 42 to be drawn toward each other until the perforations 39 and 40 are once more just within the edges 49 and 50 of the sheet 18, the spring 107 yielding to permit the two blocks to move toward each other just as the spring 104 yielded to permit the blocks to separate. 100 The parts will remain in this position as long as the apertures 51 and 52 remain uncovered by the edges of the sheet. As soon as they are again covered the two primary bellows 67 and 68 again collapse, thus cutting off the bellows 91 from communication with the exhaust chamber 71, and thereby permitting the spring 107 to slide the blocks 41 and 42 once more to their normal position with the apertures 39 and 40 again in proper 110 position, within the edges of the sheet. The momentary uncovering of the apertures 39 and 40 which takes place at the same time that the apertures 51 and 52 are uncovered permits the two motor bellows 33 and 34 to 115 exhaust and pull against each other; but this action is at once terminated by the movement of the sliding blocks 41 and 42 which carry the apertures 39 and 40. 120

The apertures 39, 40, 51 and 52 may be, 130

and preferably are made long and narrow like the apertures 53 and 54, since such a shaped duct will respond more quickly to slight variations in the paper. The ducts 5 are herein shown of different shapes, mainly in order to enable them to be distinguished and kept in mind more readily. For the same reason, the two apertures 51 and 53 and the two apertures 52 and 54 are shown 10 to be farther apart than they would be placed in regular practice.

In Fig. 14 is shown a modified form of exhaust chest 163, which may be used in place of the exhaust chest 65 of Figs. 1, 4, 5, 6 and 15 7. The exhaust chamber 165 is connected with the vacuum apparatus by the tube 166. The passage 171 connects the chamber 165 with the chamber 164. When both apertures 51 and 52 are closed, the passage 171 20 is closed at one end by the valve 170 and at the other end by the valve 169. The stem 172 of the former valve rests upon the movable leaf of the primary bellows 168. The interior of this bellows is connected with the tube 59 leading to the aperture 51. The 25 valve 169 is appurtenant to the movable leaf of the primary bellows 167 connected to the tube 60 leading to the aperture 52. A spring 172 holds the valve 169 against the opening 30 171. The uncovering of the aperture 51 expands the bellows 168 and causes the valve 170 to rise and close the opening 174 which connects the chamber 164 with the atmosphere. The uncovering of the aperture 52 35 causes the bellows 167 to expand and thereby withdraw the valve 169 from the opening 171, thus permitting the chamber 164 to exhaust and collapse the motor bellows 91. The opening of either passage 51 or 52, separately, however, will not collapse the motor 40 bellows 91, as the chamber 164 will not exhaust until both valves 170 and 169 are moved from the passage 171.

Fig. 15 shows a modified form of exhaust 45 box 180, which may be used in place of the exhaust box 121 of Figs. 1, 8, 9, 10 and 11. In this case the covering of the two apertures 53 and 54 will cause the two primary bellows 184 and 185 to be exhausted through 50 their bleedholes, thus collapsing the bellows and thereby uncovering the passage 188 leading from the exhaust chamber 182 to the chamber 181. When the bellows 184 collapses, the spring 189 raises the valve 186 55 by means of its stem 190, and closes the opening 191, thus permitting the chamber 181 to exhaust and collapse the motor bellows 116 through the tube 120. The closing of either aperture 53 or 54 alone will not 60 operate the motor bellows 116, as the passage 188 will still be closed by either the valve 186 or the valve 187, and therefore the chamber 181 will not be exhausted.

Fig. 16 shows a modified form of exhaust 65 box 200 which may be used in place of the

exhaust box 65 of Figs. 1, 4, 5, 6 and 7. The uncovering of both apertures 51 and 52 will cause the two primary bellows 204 and 205 to expand, the former lowering the valve 210 so as to open the passage 208 between 70 the exhaust chamber 202 and the upper chamber 201. The pallet 206 being secured to the valve stem 211 is also lowered and closes the opening 213 to the atmosphere, and permits the chamber 201 to exhaust. 75 At the same time the expanding of the bellows 205 permits the valve 207 to drop as the stem 212 rests upon the movable leaf of the bellows 205. The motor bellows 91 is therefore collapsed through its connection by the 80 tube 90 with the chamber 101. The opening of either passage 51 or 52 alone, however, will not operate the motor bellows 91, as either the passage 208 will be covered by the valve 210, or the end of the tube 90 will 85 be covered by the valve 207.

It will be noted that the two sets of primaries which operate the motor bellows are the reverse of each other in their mode of action. The primaries 67 and 68 are normally collapsed and act on the motor bellows 91 by expanding when the apertures 51 and 52 are uncovered; whereas the primaries 126 and 127 are normally expanded and act upon the motor bellows 116 by collapsing when 95 the apertures 53 are covered. This characteristic of the arrangement of the primary pneumatics whereby their operation requires the coöperation of two different apertures, constitutes a joint control device which is of 100 great utility for many other purposes than those herein described. Not only may this joint control be exercised by means of the margins of the sheet as herein shown, but it may be arranged to operate in connection 105 with a single perforation or a plurality of perforations. In Fig. 17 is shown an instance in which two apertures 193 and 194 corresponding to apertures 51 and 52 are arranged in succession in the path of the 110 same perforation 195 of the note sheet 196. When this perforation occupies the position shown in the drawing, both apertures are uncovered and the connected motor will therefore be operated. When the perforation is 115 in the position corresponding longitudinally to 197 and 198, only one of the apertures is uncovered and the motor bellows will therefore not operate.

In the forms of primary boxes shown in 120 Figs. 8 and 11 and in Figs. 14, 15 and 16, the motor pneumatics 91 and 116 would require "bleed holes" to enable them to expand in some of the positions which the parts might assume after the exhaust has 125 been cut off from the motor pneumatics. An arrangement is shown in Fig. 18 by which the expansion of the motors may be otherwise provided for. A flap valve 146 is provided in the top of the box 121, and 130

valve is held open by means of the pin 147 when the pallet 140 is in its upper position, thus opening the bellows 91 to the atmosphere through the passage 148. When the pin 147 is withdrawn the flap valve 146 closes so as to permit the bellows 91 to exhaust whenever required.

If desired, the tracker 19 may be held in a fixed position in the uprights by means of the set screws 43; and then by loosening the set screws 44 the operation of the motor bellows 33 and 34 will shift the roll 21 sidewise instead of shifting the tracker, thus bringing the sheet and the tracker into proper relation as before.

15 The terms "upper," "lower," "right," "left," etc. are here used in their relative and not their absolute sense, as it is obvious that many of the parts of the apparatus may 20 be altered, inverted or transposed according to the judgment of the designer or builder, without in any way affecting the spirit of this invention.

It is also obvious that the apparatus may 25 be made to work with pressure instead of exhaust by such changes in the arrangement of the parts as will readily suggest themselves to the expected skill, knowledge or judgment of the maker.

30 The valve and bellows are herein shown conventionally and more or less incomplete as to springs and other details. It is understood that these will be adapted and varied to suit various positions, and different conditions of service.

35 The function of the motor pneumatics being of a nature that does not require rapid action, the construction of the parts may accordingly vary somewhat from the usual 40 forms.

I am aware also that many other changes can be made in the apparatus by any person skilled in the art without departing from the scope of the invention as expressed in the 45 claims. Therefore I do not wish to be limited to all the details of construction shown and described, but

I claim as my invention:

50 1. The combination with a perforated traveling web and tracker, of pneumatic apparatus for shifting the relative positions of the web and tracker, the tracker having a plurality of ducts arranged adjacent to the edges of the web when in operation on the tracker, a pneumatic motor, and means not controlled by the ducts along either edge alone, but controlled by the ducts along both edges in coöperation for inaugurating the operation of the motor.

55 60 2. The combination of a tracker, means for drawing a web over the tracker, pneumatic apparatus for adjusting the lateral relation between the tracker and web, a guide opening connected to control the 65 operation of said apparatus, and means for

automatically adjusting said guide opening laterally so that the same will coöperate with webs of different widths.

3. The combination, in pneumatic apparatus of a pneumatic motor, a pair of 70 ducts, and means controlled by the coincident covering of the ducts for inaugurating the operation of the pneumatic motor.

4. The combination, in pneumatic apparatus, of a pneumatic motor, a pair of 75 ducts, and means inoperative by the separate uncovering of the ducts, but operative by the coincident uncovering of the ducts for inaugurating the operation of the pneumatic motor.

80 5. The combination of a tracker, means for drawing a web over the tracker, pneumatic apparatus for adjusting the lateral relation between the tracker and web, two guide openings connected to control the 85 operation of said apparatus, and means for automatically adjusting said guide openings laterally of the web so that the same will coöperate with webs of different widths.

6. The combination of a tracker, means 90 for drawing a web over the tracker, pneumatic apparatus for adjusting the lateral relation between the tracker and web, two guide openings connected to control the 95 operation of said apparatus, and means for adjusting said guide openings laterally of the web so that the same will coöperate with webs of different widths, comprising two pairs of openings, each pair arranged so that one will come under the edge of the 100 web and the other outside of the web, and pneumatic apparatus connected to said two pairs of openings and arranged to adjust the guide openings.

7. The combination of a tracker, means 105 for drawing a web over the tracker, pneumatic apparatus for adjusting the lateral relation between the tracker and web, two guide openings connected to control the 110 operation of said apparatus, and means for adjusting said guide openings laterally of the web so that the same will coöperate with webs of different widths, comprising two pairs of openings, each pair arranged so that one will come under the edge of the 115 web and the other outside of the web, valve apparatus controlled by said two pairs of openings, and pneumatic apparatus controlled thereby and connected to adjust the guide openings.

8. The combination, with a traveling sheet or web, of means for guiding or restoring the web to its desired path when diverted therefrom, and means contacting with the surface of the web and held out of operation while the web is of normal width, for moving the restoring means into operable relation to the web upon the lateral expansion of the latter.

125 9. The combination, with a traveling sheet 130

- or web, of means for guiding or restoring, in inoperative relation by the sheet when in its normal position for restoring the normal relation of the sheet and the tracker when uncovered by either edge of the sheet, contact devices one at each end of the tracker 70 while the web is of normal width, for moving the restoring means into operable relation to the web upon the lateral contraction of the latter.
10. The combination, with a traveling sheet or web, of means for guiding or restoring the web to its desired path when diverted therefrom, and means contacting with the surface of the web and held out of operation while the web is of normal width, for moving the restoring means into operable relation to the web upon the lateral expansion or contraction of the latter. 75
11. The combination, with a traveling sheet or web, of means for guiding or restoring the web to its desired path when diverted therefrom, of means for moving the restoring means into operable relation to the web when the latter expands or contracts laterally, and means, contacting with the surface of the web and held out of operation when the web is of normal width, for inaugurating the operation of the moving means. 80
12. The combination with a tracker and a traveling sheet or web, of means for guiding or restoring the web to its desired path when diverted therefrom, means for moving the restoring means into operable relation to the web when the latter expands or contracts laterally, and means contacting with the marginal surface of the web and held out of operative relation thereby when the web is of normal width, for inaugurating the operation of the moving means. 85
13. The combination with an apparatus employing a traveling sheet or web, of means for guiding or restoring the web to its desired path when diverted therefrom, means for inaugurating the operation of the restoring means and held out of operative relation therewith by the margin of the sheet when the sheet is traveling in its desired path, and means for moving the inaugurating means into operable relation with the margin of the sheet when the latter expands or contracts laterally. 90
14. The combination, with a traveling sheet or web, of a tracker, means maintained in inoperative condition by the sheet when in its normal position for restoring the normal relation of the sheet and the tracker when uncovered by either edge of the sheet, and means for moving the restoring means into proper relation to the edges of the sheet 100 when the latter expands or contracts laterally, said moving means being maintained in inoperative relation by the sheet when the latter is of normal width. 105
15. The combination, with a traveling sheet or web, of a tracker, means maintained in inoperative relation by the sheet when in its normal position for restoring the normal relation of the sheet and the tracker when uncovered by either edge of the sheet, contact devices one at each end of the tracker 110 arranged adjacent to and inside of the normal position of the edges of the sheet when the sheet is of normal width, so as to be covered by the marginal surface of the sheet when the latter is in its normal position, and means operable by the uncovering of the contact devices for moving the restoring means inward into proper relation to the edges of the sheet. 115
16. The combination, with a traveling sheet or web, of a tracker, means maintained in inoperative relation by the sheet when in its normal position for restoring the normal relation of the sheet and the tracker when uncovered by either edge of the sheet, contact devices one at each end of the tracker 120 arranged adjacent to and outside of the normal position of the edges of the sheet when the sheet is of normal width, so as to be left uncovered by the marginal surface of the sheet when the latter is in its normal position, and means operable by the covering of the contact devices for moving the restoring means outward into proper relation to the edges of the sheet. 125
17. The combination, with a traveling sheet or web, of a tracker, means maintained in inoperative relation by the sheet when in its normal position for restoring the normal relation of the sheet and the tracker when uncovered by either edge of the sheet, contact devices one at each end of the tracker 130 arranged adjacent to and inside of the normal position of the edges of the sheet when the sheet is of normal width, so as to be covered by the marginal surface of the sheet when the latter is in its normal position, contact devices one at each end of the tracker arranged adjacent to and outside of the normal position of the edges of the sheet when the sheet is of normal width, so as to be uncovered by the marginal surface of the sheet when the latter is in its normal position, and means operable by the uncovering of the first contacts for moving the restoring means inward or by the covering of the second contacts, for moving the restoring means outward, into proper relation to the edges of the sheet. 135
18. The combination, with a traveling sheet or web, of a tracker, means maintained in inoperative relation by the sheet when in its normal position, for restoring the normal relation of the sheet and the tracker when uncovered by either edge of the sheet, pneumatic devices for moving the restoring means into proper relation to the edges of the sheet when the latter expands or contracts laterally; a pair of contact devices, one at each end of the tracker, located inside 140

the normal position of the edges of the sheet when the sheet is of normal width, and a pair of contact devices one at each end of the tracker, located outside the normal position of the edges of the sheet when the sheet is of normal width, the operation of the pneumatic devices being inaugurated by the lateral contraction of the web in uncovering one pair of contact devices, or by the lateral 10 expansion of the web in covering the other pair of contact devices.

19. The combination, with a traveling sheet or web, of a tracker, means maintained in operative relation by the sheet when in its 15 normal position for restoring the normal relation of the sheet and the tracker when uncovered by either edge of the sheet, pneumatic devices for moving the restoring means into proper relation to the edges of 20 the sheet when the latter expands or contracts laterally, a pair of contact devices, one at each end of the tracker, located inside the normal position of the edges of the sheet when the sheet is of normal width, a pair of 25 contact devices one at each end of the tracker, located outside the normal position of the edges of the sheet when the sheet is of normal width, the operation of the pneumatic devices being inaugurated by the lateral 30 contraction of the web in uncovering one pair of contact devices, or by the lateral expansion of the web in covering the other pair of contact devices, and means for varying 35 the relative positions of the two pairs of contact devices to provide for webs of different normal widths.

20. The combination of pneumatic pressure producing devices, a motor bellows, a communication from the pressure producing 40 devices to the motor bellows, a perforated traveling web, a tracker, means for shifting the relative positions of the web and tracker communicating with said pressure producing devices, two primary bellows provided 45 with independent operating passages normally closed to the atmosphere, and coöperating to open the said communication only when both passages are open to the atmosphere.

50 21. The combination of pneumatic pressure producing devices, a motor bellows communicating therewith, two primary bellows provided with independent operating passages normally open to the atmosphere, 55 and jointly operating to open the said communication only when both of said passages are closed to the atmosphere.

22. The combination in pneumatic devices, of a motor bellows and means including a pneumatic primary box for operating the motor bellows containing two primary bellows provided with independent operating passages normally closed to the atmosphere, and means operated by the two primary bellows whereby the opening of both

passages to the atmosphere is required to operate the motor bellows.

23. The combination, in pneumatic devices, of a motor bellows, and means including a pneumatic primary box for operating the motor bellows, containing two primary bellows provided with independent operating 70 passages normally open to the atmosphere, and means operated by the two primary bellows, whereby the closing of both 75 passages to the atmosphere is required to operate the motor bellows.

24. The combination in pneumatic devices of a vacuum chamber, an air chamber, a passage between the said chambers, a passage to the atmosphere from the air chamber, a motor bellows communicating with the air chamber, a pair of operating ducts, a pair of primary pneumatics in the vacuum chamber communicating with the said ducts, 80 and valves operated by the primary pneumatics and jointly controlling the communication between the vacuum chamber and the said motor, whereby the contemporaneous 85 action of the two primary pneumatics is required to collapse the motor bellows.

25. The combination in pneumatic devices of a vacuum chamber, an air chamber, a passage between the said chambers, a passage to the atmosphere from the air chamber, a motor bellows communicating with the air chamber, a pair of operating ducts, a pair of primary pneumatics in the vacuum chamber connected with the said ducts, and a valve operated by the primary pneumatics 95 and jointly controlling the passages between the vacuum chamber and the motor bellows, whereby the contemporaneous collapsing of 100 the two primary pneumatics is required to collapse the motor bellows.

26. The combination in pneumatic devices of a vacuum chamber, an air chamber, a motor bellows, passages connecting the vacuum chamber, air chamber and motor bellows, a passage to the atmosphere from the air chamber, a pair of operating ducts, a pair of primary pneumatics in the vacuum chamber communicating with the said ducts, and valves operated by the said primary pneumatics for opening and closing the said 110 passages, and thereby jointly controlling the operation of the motor bellows.

27. The combination in pneumatic devices of a vacuum chamber, an air chamber, a motor bellows, passages connecting the vacuum chamber, air chamber and motor bellows, a passage to the atmosphere from the air chamber, a pair of controlling ducts, a pair of primary pneumatics in the vacuum chamber communicating with the said ducts, 120 a valve in the air chamber connected to one of the primary pneumatics and operating to close the vacuum passage when its pneumatic is expanded and to close the atmosphere passage when its pneumatic is col- 125 130

lapsed, and a valve in the vacuum chamber connected to the other primary pneumatic and operating to close the passage leading to the air chamber when the pneumatic is expanded.

28. The combination in an instrument of the class specified, of a tracker provided with a series of note ducts and with an adjacent guide opening, and automatic means for adjusting the position of the said guide openings longitudinally, relatively to the adjacent series of note ducts.

29. The combination in an instrument of the class specified, of a tracker provided with a guide opening, automatic means and 15 manually operated means for adjusting the said opening laterally of the sheet.

In testimony whereof I have signed my name to this specification in the presence of two subscribing witnesses.

JAMES O'CONNOR.
